SAFETY APPLIANCE.

Application filed July 5, 1923. Serial No. 649,567.

This invention relates to improvements in safety appliances, and refers more particularly to a safety relief valve or pressure valve arrangement whereby excess pressures upon apparatuses are automatically relieved.

Among the objects of the invention are to provide safety appliances particularly adapted to be used on high pressure apparatuses to automatically function when an excess pressure is imposed, to relieve the pressure on the system; to provide a device adapted to be used with oil cracking systems in which substantial pressure is maintained upon the oil undergoing treatment, whereby excess pressures may be relieved and simultaneously a quenching medium added to the exhausted vapors to reduce the combustible gases to a relatively inert vapor.

Fig. 1 is a diagrammatic view of a cracking apparatus with the appliance installed. Fig. 2 is an enlarged detail of the upper portion of the expansion chamber showing the device in section. Fig. 3 is a detail taken along the line 3—3 in Fig. 2, looking in the direction of the arrows. Fig. 4 is a detail taken along the line 4—4 in Fig. 2, and Fig. 5 is a view taken along the line 5—5 in Fig. 4.

Although the device is shown in connection with an oil cracking system, it is understood that it may be used in connection with any type of pressure system in which it is desirable to have a safety valve or relief arrangement for releasing excessive pressures in the system, and which cannot be otherwise exhausted, such safety valve arrangement being desirable to prevent hazardous and excessive strain upon the parts.

In Fig. 1 at 1 is shown a heating coil mounted in a furnace 2. This coil is connected by means of a transfer line 3 to an expansion chamber 4. The expansion chamber in turn has a vapor line connection 5 to a fractionating tower 6, the latter being connected by line 7 to a condensing coil 8 and by a line 9 to the charging line 10 by means of which the oil to be treated, is introduced to the system. The discharge end of the condenser coil is connected by a pipe 11 to a receiving tank 12, the latter being equipped with a pressure relief valve 13, liquid draw-off valve 14, pressure gauge 15 and liquid level gauge 16. The oil on being introduced to the system through the line 10 is heated to a conversion temperature, permitted to vaporize in the expansion chamber, from which

the vapors pass off to the fractionating tower, thence to the condenser and are collected as liquid in the distillate receiver 12, the reflux condensate passing back from the fractionating tower through the line 9 to be retreated in the heating coil, and the unvaporized products from the expansion chamber being drawn off through either of the drawoff lines 17 controlled by suitable valves 18.

This brief explanation of the system will serve to explain the application of the device, but it is understood that it may be applied to any pressure system in order to relieve excessive pressures.

The device itself consists of a metal diaphragm 19 which has been tested to rupture at a predetermined pressure. This diaphragm as shown in Fig. 2 is interposed between the flanges in a relief pipe 20. The diaphragm is preferably of metal either steel, aluminum, copper, iron or any other metallic substance, it being essential only that its bursting strength is accurately determined. Below the diaphragm 19 and interposed in the same relief pipe is a second diaphragm 21 shown in Fig. 3, which has a small perforation 22. The interposition of this diaphragm below the upper safety diaphragm is to prevent the circulation of uncondensable vapors up and down the pipe and cause undue heating of the upper diaphragm, the heat effecting the bursting strength of the safety disk. The aperture in the center of the lower diaphragm 21 serves also to equalize the pressure between the two diaphragms and the pressure upon the system.

Preferably the lower diaphragm should be of less thickness than the upper diaphragm so as to rupture simultaneously or just prior to the bursting of the upper diaphragm. Above the relief pipe 20 is positioned an open ended funnel shaped member 26, which has positioned therein an upturned steam pipe 23. This steam pipe is preferably capped by a fusible plug 24 which will melt at a predetermined temperature and permit steam or water from the pipe 23 to spray into the vapors relieved from the system. The introduction of a steam or water spray into the hydrocarbon vapors, or similar combustible vaporous fluids, will serve to quench and extinguish the combustible materials as they are exhausted from the system. By use of the air inducer nozzle which draws air upwardly through the lower portion of the funnel 26 and ex-

hausts it with the vapors, the vapors are cooled and reduced in temperature, consequently less liable to flash. The fusible plug on the steam or water pipe melting with the 5 exhausting of the vapors, injects this quenching medium into the vapors and further reduces their temperature.

By the use of a safety diaphragm inserted in the manner explained, a simple, inexpensive safety valve arrangement is provided for relieving excessive pressures upon the system. It is reliable, as the diaphragms can be tested to bursting pressure, and they are ruptured within sufficiently close range as to not 10 unduly strain the parts of the apparatus. Further, the device cannot get out of order or become inoperative as does the ordinary safety valve of the spring or lever type. These 15 diaphragms may be equipped with a tongue or lug shown at 25 on the separate diaphragms, stamped with the pressure at which the safety rings or disks will rupture.

We claim as our invention:

1. A safety device for an element of an oil cracking apparatus comprising a relief pipe, 25 a plate positioned in said relief pipe, said plate having a predetermined rupturing strength, a funnel-shaped member positioned above said relief pipe, a steam pipe terminating in said funnel-shaped member, and a 30 fusible plug closing the end of said steam pipe.

2. A safety device for an element of an oil cracking apparatus comprising an outlet pipe, means in said outlet pipe adapted to be 35 ruptured when the pressure in said element exceeds a predetermined value, a funnel-shaped member positioned about the discharge end of said outlet pipe, a steam line terminating in said funnel-shaped member, 40 and a fusible plug positioned at the end of said steam line.
